(57) **CLAIM**

The design for an inoculation loop device with angled end, as shown and described.

DESCRIPTION

FIG. 1 is a side elevational view of an inoculation loop device with an angled end;

FIG. 2 is a side view of the inoculation loop device with an angled end;

FIG. 3 is a bottom view of the inoculation loop device with an angled end;

FIG. 4 is a top view of the inoculation loop device with an angled end;

FIG. 5 is an end view of the inoculation loop device with an angled end as viewed from a left-hand side to a right-hand side of the inoculation loop device with an angled end shown in FIG. 2; and,

FIG. 6 is an end view of the inoculation loop device with an angled end as viewed from a right-hand side to a left-hand side of the inoculation loop device with an angled end shown in FIG. 2.

The broken line showing of parts of the drawings is included for the purpose of illustrating use and environment and forms no part of the claimed design.
